CLAIM

The ornamental design for a water treatment cabinet, as shown and described.

DESCRIPTION

FIG. 1 is a perspective view of the water treatment cabinet in accordance with our invention;

FIG. 2 is a left side view of the invention of FIG. 1;

FIG. 3 is a front view the invention of FIG. 1;

FIG. 4 is a right side view of the invention of FIG. 1;

FIG. 5 is a rear view of the invention of FIG. 1; and,

FIG. 6 is a top view of the invention of FIG. 1.

In the drawings, the broken lines and adjacent unshaded areas illustrate portions of the water treatment cabinet that form no part of the claimed design.
